(57) **CLAIM**

The ornamental design of an adjustable wand for a vacuum cleaner, as shown and described.

DESCRIPTION

FIG. 1 is a perspective view of an adjustable wand for a vacuum cleaner showing our new design according to one embodiment;

FIG. 2 is a front view thereof;

FIG. 3 is a back view thereof;

FIG. 4 is a left side view thereof;

FIG. 5 is a right side view thereof;

FIG. 6 is a perspective view of the adjustable wand for a vacuum cleaner connected to a hand vacuum component and a surface cleaning head component; and

FIG. 7 is a perspective view of the adjustable wand for a vacuum cleaner in a bent configuration and connected to a hand vacuum component and a surface cleaning head component.

FIG. 8 is a perspective view of an adjustable wand for a vacuum cleaner showing our new design according to one embodiment;

FIG. 9 is a front view thereof;

FIG. 10 is a back view thereof;

FIG. 11 is a left side view thereof;

FIG. 12 is a right side view thereof; and,

FIG. 13 is a perspective view of the adjustable wand for a vacuum cleaner in a bent configuration and connected to a hand vacuum component and a surface cleaning head component.

The broken lines are included for the purpose of illustrating the unclaimed portions of the article and form no part of the claim.
